Roger M. Snook, San Francisco, Calif., assignor of one-half to Henry Gifford Hardy, Berkeley, Calif.

Application June 15, 1954, Serial No. 30,993

Term of patent 14 years

(Cl. D80—8)

To all whom it may concern:

Be it known that I, Roger M. Snook, a citizen of the United States of America, residing at 733 Congo Street, San Francisco, State of California, have invented a new, original, and ornamental Design for a Coat Hanger, of which the following is a specification, reference being made to the accompanying drawing, forming a part hereof.

upper portion of said coat hanger, including the grip and the hook.

I claim:

The ornamental design for a coat hanger, as shown.
